UNITED STATES PATENT OFFICE.

BRUCE E. ROSE, OF STOCKTON, CALIFORNIA.

HARROW-DISK CONTROL.

Application filed April 25, 1927. Serial No. 186,244.

This invention relates to improvements in control means for disk harrows of that type in which gangs of disks are mounted on horizontally swinging frames. These frames are normally set so that the disks are angularly disposed to the line of travel of the implement, and in harrowing operations it is necessary at times to turn the frames so as to place the disks in a straight fore and aft alignment.

The control devices at present used for this purpose all, as far as I am aware, necessitate backing up of the tractor or other draft means either to straighten out the disks or to return them to their angular positions; while manually operated means is employed to impart the movement to the disk frames in the other direction. This is inconvenient, as it requires frequent halting of harrowing operations to effect the above described movement of the disks, and a consequent loss of time is had.

The principal object of my invention is to eliminate this objectionable feature by providing a control means for the disk frames, so arranged that both the straightening out and return movement of the disks to their angular positions is accomplished with a continuous forward movement of the harrow.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a top plan view of my improved harrow and its control means.

Fig. 2 is an enlarged longitudinal view of the control device showing the lever in its normal position.

Fig. 3 is a fragmentary longitudinal view of the control structure showing the position of the control lever and pawls when the latter are disengaged from the drawbar.

Fig. 4 is an enlarged cross section on the line 4-4 of Fig. 2.

Referring now more particularly to the characters of reference on the drawings, the structure comprises a substantially pentagon shaped main frame 1 below which are dis-

posed yoke frames arranged as front and rear pairs 2 and 2^a which support the gangs of disks 3. Each disk supporting frame is pivotally supported from the main frame for horizontal swinging movement by means of vertical spindles 4 on said frames turnable in bearing sleeves 5 on the frame 1 preferably at the corners of the latter.

The pivot of the forward pair of frames 2 is between the two outermost disks and these frames normally have a rearward slope toward the center of the main frame so that the disks carried thereby are normally disposed at a forward angle to the line of travel. The pivots of the rear pair of frames 2^a are disposed between the two innermost disks and said frames normally have a rearward slant toward toward their outer ends so that the corresponding disks are also disposed at an angle to the line of travel opposite to that of the forward gangs of disks. Owing to this arrangement the forward pull on the structure tends to cause the angular setting of all the disks to be maintained and to be increased if not prevented from so doing.

The disks are controlled as to their angular setting, straightened out when desired and again moved to their angular positions by the following structure:

Mounted on the frame 1 at its forward end are longitudinally extending guide members 6, between which a drawbar 7 is slidable. Longitudinal movement of the drawbar is limited by transverse pins 8 therein which ride in longitudinal slots 9 provided in the guides. Links 10 extend between the rear end of the drawbar and the forward frames 2 inwardly of their pivots; while similar links 11 extend from the said frames 2 inwardly of their pivots to connections with the corresponding rear frames 2^a outwardly of the pivots thereof. The distance from the pivots of the frames 2 to the connection of the links 11 therewith is the same distance as from the pivots of the frames 2^a to said links so that a movement of the frames 2 through a certain arc will impart the same arcuate movement of the frames 2^a. Each of the links is preferably formed of rods or the like, slidably connected together so as to form a rigid non-yieldable element when pulled but which can give when pushed. This permits a backing up of the drawbar and harrow structure without tending to bend the links.

The under face of the drawbar is pro-

vided with forwardly facing ratchet teeth the various pivots 4 to be moved forwardly 12 engaged by a rearwardly projecting spring 5 also, the disk supporting frames then swinging on the connection of the links therewith between the drawbar and the guides (and as pivots. This restores the angular setting to the disk units, such setting of course 70 consequently the frame structure) when a pull is exerted on the drawbar.

Pivoted on a bracket 14 projecting upwardly from and mounted on the guide members 10 is a lever 15, the lower portion of which is formed with forked arms 15^a which straddle the guides and depend therebelow. The upper portion of the lever is held at a rearward angle by a spring 16 and has a forwardly extending pull cable 17 connected thereto so that the lever may be pulled against the pressure of the spring from any suitable distance ahead of the harrow. Pivoted 15 between the arms 15^a below the drawbar is a 20 spring pressed pawl 18 normally engaging one of the teeth 12 to the rear of that engaged by the pawl 13. The pawl 18 has a rearward and downwardly projecting extension 19 which, after a certain rearward movement 25 of the adjacent portion of the lever has taken place, engages a transverse trip pin 20 fixed in connection with the guides.

The pin and extension are so disposed that after the pin initially engages the extension, 30 a continued rearward movement of the lever causes the pawl 18 to be depressed clear of the teeth 12. At the same time the pawl 13 will also be disengaged from the drawbar teeth by means of a flexible element 21 connected to said pawl and to the lower end of 35 the lever. By means of this construction it will be seen that with a continued pull on the drawbar, while the disk units are in their normal angular positions, a pull on the lever 40 a sufficient distance to disengage the pawls from said drawbar will cause the latter to be released from the guides and frames for longitudinal movement relative thereto, to the extent permitted by the slots 9 and pins 45 8. The pull on the drawbar will therefore be transmitted through to the links and consequently the disk units will be straightened out so that the disks will be in direct alignment with the path of movement of the implement, at which position the pins 8 engage 50 the forward ends of the slots 9 as shown in Fig. 3. When it is desired to again move the disks to an angular position the lever is pulled once or reciprocated as many times as necessary, the arcuate movement of the lever being just sufficient to maintain the pawls in engagement with the drawbar, without causing the trip pin to be engaged with the extension of the pawl 18. These movements of 55 the lever will of course cause the drawbar to move rearwardly relative to the guides and main frame. Since the drawbar is anchored to the forwardly moving draft means, the action actually obtained is a forward movement of the frame 1. This of course causes 60

the various pivots 4 to be moved forwardly also, the disk supporting frames then swinging on the connection of the links therewith as pivots. This restores the angular setting to the disk units, such setting of course 70 depending on how many reciprocations has been given the lever, and at which point in the length of the drawbar the fixed pawl 13 then engages the same.

The position of the pivots on the disk supporting frames and the arrangement of the pivots of the front frames relative to those on the rear frames is such that the ground pressure thereagainst acts on all frames to the same extent and in the same direction 80 such as will tend to restore and maintain the frames in an angular setting. This obviously reduces to a minimum the physical effort necessary to operate the lever in a disk resetting position.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A harrow including a main frame, a disk-supporting frame pivoted thereon for horizontal swinging movement, a drawbar mounted on the main frame for longitudinal sliding movement relative thereto, a connection between the drawbar and the disk-supporting frame, means for normally holding the drawbar against forward movement relative to the main frame, a lever mounted in connection with said main frame, means between the lever and drawbar for moving the main frame forwardly relative to the drawbar with a movement of the lever for a certain distance in one direction, and means between the lever and said holding means for releasing the latter with a movement of said lever a further distance in the same direction.

2. A harrow including a main frame, a disk-supporting frame pivoted thereon for horizontal swinging movement, a drawbar mounted on the main frame for longitudinal sliding movement relative thereto, a connection between the drawbar and the disk-supporting frame, means for normally holding the drawbar against forward movement relative to the main frame, a lever mounted in connection with said main frame, means controlled by the movement of the lever a certain distance in one direction for moving the main frame forwardly relative to the drawbar, and means controlled by a movement of the lever

a further distance in the same direction for moving the lever-pawl clear of the drawbar-teeth. 45

3. A harrow including a main frame, a disk-supporting frame pivoted thereon for horizontal swinging movement, a drawbar mounted on the main frame for longitudinal sliding movement relative thereto, a connection between the drawbar and the disk-supporting frame, one face of the drawbar having forwardly facing ratchet teeth thereon, a pawl normally engaging one of said teeth, a lever pivoted in connection with the main frame, a pawl on said lever to engage said ratchet teeth whereby when the lower end of the lever is moved rearwardly a certain distance the frame will be moved forwardly relative to the drawbar, means between the lever and said first named pawl for pulling the same clear of the drawbar teeth when said lever is moved a further distance rearwardly, and means controlled by such further movement of the lever for also moving the lever-pawl clear of the drawbar-teeth. 60

4. A harrow including a main frame, a disk-supporting frame pivoted thereon for horizontal swinging movement, a drawbar mounted on the main frame for longitudinal sliding movement relative thereto, a connection between the drawbar and the disk-supporting frame, one face of the drawbar having forwardly facing ratchet teeth thereon, a pawl normally engaging one of said teeth, a lever pivoted in connection with the main frame, a pawl on said lever to engage said ratchet teeth whereby when the lower end of the lever is moved rearwardly a certain distance the frame will be moved forwardly relative to the drawbar, a normally slack flexible connection between said first named pawl and the lower end of the lever arranged to cause said pawl to be moved clear of the drawbar-teeth when the lever is moved a further distance rearwardly, and means controlled by such further movement of the lever for also 65

5. A harrow including a main frame, a disk-supporting frame pivoted thereon for horizontal swinging movement, a drawbar mounted on the main frame for longitudinal sliding movement relative thereto, a connection between the drawbar and the disk-supporting frame, one face of the drawbar having forwardly facing ratchet teeth thereon, a pawl normally engaging one of said teeth, a lever pivoted in connection with the main frame, a pawl on said lever to engage said ratchet teeth whereby when the lower end of the lever is moved rearwardly a certain distance the frame will be moved forwardly relative to the drawbar, means between the lever and said first named pawl for pulling the same clear of the drawbar-teeth when said lever is moved a further distance rearwardly, a fixed trip member mounted rearwardly of the normal travel of the lever-pawl, and a rearward extension on said lever pawl to engage and ride against said member with such further movement of the lever; the extension being arranged to then cause the lever pawl to be pulled clear of the drawbar-teeth. 70

6. A harrow including a main frame, a disk-supporting frame pivoted thereon for horizontal swinging movement, a drawbar mounted on the main frame for longitudinal sliding movement thereto, a connection between the drawbar and the disk supporting frame, forwardly facing ratchet teeth cut on the under side of the drawbar, a lever pivoted intermediate its ends on the main frame 75 and depending below the drawbar, and a rearwardly facing pawl on the lower end of the lever normally engaging the teeth whereby a forward pull on the upper end of the lever will cause the frame to be moved forwardly relative to the drawbar. 80

In testimony whereof I affix my signature.
